(57) **CLAIM**

The ornamental design for a computer device support stand, as shown and described.

DESCRIPTION

FIG. 1 is a front perspective view of a computer device support stand showing our new design and showing the computer device support stand adjusted for supporting a computer device at a de-elevated height;

FIG. 2 is another front perspective view of the computer device support stand shown in FIG. 1, showing the computer device support stand adjusted for supporting a computer device at an elevated height;

FIG. 3 is a front elevational view thereof with the de-elevated height adjustment shown in FIG. 1;

FIG. 4 is a left side elevational view thereof, the right side being a mirror image;

FIG. 5 is a rear elevational view thereof;

FIG. 6 is top plan view thereof; and,

FIG. 7 is a bottom plan view thereof.

The two broken line rectangles in FIG. 5 immediately below the shaded areas represent the bounds of the claimed design while all other broken lines represent portions of the computer device support stand that form no part of the claimed design. The broken lines form no part of the claimed design.

1 Claim, 6 Drawing Sheets
